UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKING APPARATUS

Application filed April 8, 1930. Serial No. 442,509.

My invention relates to railway braking apparatus, and particularly to apparatus of the type comprising braking bars located in the trackway and arranged to be moved at times into engagement with the wheels of a railway car.

I will describe one form of apparatus embodying my invention, and will then point out the novel features thereof in claims.

10 In the accompanying drawings, Fig. 1 is a top plan view showing one form of braking apparatus embodying my invention with some of the parts broken away to illustrate the construction. Fig. 2 is a view partly in 15 elevation and partly in section substantially along the lines II-II of Fig. 1. Fig. 3 is a view partly in elevation and partly in section substantially along the line III-III of Fig. 1. Figs. 4 and 5 are sectional views showing 20 portions of the apparatus illustrated in Fig. 1 on a somewhat larger scale. Fig. 6 is a left-hand end view of the guide rail G illustrated in Fig. 1.

Similar reference characters refer to similar parts in each of the several views.

Referring first to Figs. 1, 2 and 3, the reference characters 1 and 1^a designate the track rails of a stretch of railway track, supported by rail supports 2 secured to the usual cross-ties 3, and over which traffic normally moves in the direction indicated by the arrow. Extending parallel with rail 1 are two pairs of stringers, one pair 4 and 5 being located on one side of the track rail, and the other pair 6 and 7 being located on the other side of the track rail, as best seen in Fig. 1. The two pairs of stringers are connected together at intervals by means of yokes, each designated by the reference character 8, and each extending transversely beneath the track rail and having one end interposed between stringers 4 and 5 and the other end between stringers 6 and 7. The stringers are securely fastened to the yokes by means of suitable bolts or rivets, and it will therefore be plain that the four stringers 4, 5, 6 and 7, together with the yokes 8 form a cradle for supporting the braking apparatus. In similar manner, rail 50 1^a is provided with a cradle made up of four

stringers 4^a, 5^a, 6^a and 7^a, and a plurality of yokes 8^a.

Located between the stringers 4 and 5 and the rail 1 is a braking bar B, and located between the stringers 6 and 7 and the rail 1^a is a braking bar C. In similar manner, located between the stringers 4^a and 5^a and the rail 1^a is a braking bar B^a, and located between the stringers 6^a and 7^a and the rail 1^a is a braking bar C^a. Each of these braking bars is made up of a plurality of brake beams 9, which as here shown, are connected together by means of a replaceable brake shoe D. The brake shoes D may be constructed of a single piece of slightly flexible material which extends the whole length of the retarder, as illustrated in connection with braking bar B, or they may be constructed of a plurality of flexible sections 15, as illustrated in connection with braking bar C. When the brake shoes are constructed in sections, the abutting ends of the shoes preferably will be located near the center of a brake beam and will be securely fastened to the brake beam, so that there is no chance of any misalignment which would result in shock to the retarder or the car as a car wheel passes from one brake shoe section to the next. When the brake beams are connected together in this manner, the ends of adjacent beams may be made straight, with clearance between them, as illustrated in connection with braking bar C, or each beam may be provided at one end with a vertical tongue 9^a which enters a vertical groove 9^b in the confronting end of the adjacent beam, as illustrated in connection with braking bar B. With this articulated construction, a large part of the strain to which the brake shoes are subjected when a car wheel passes from one brake beam to the next is taken up by the tongues and grooves.

As best seen in Figs. 4 and 5, each brake beam 9 rests directly on the associated yoke 8 or 8^a, and is provided with a plurality of downwardly extending projections 10, one of which is located on each side of each yoke. Secured to these projections at each yoke in any suitable manner, as by cap screw 11, and extending through a suitable opening 13 in 100

the associated yoke, is a hold down bar 12. A wearing plate 14 is fastened to each yoke 8 at the upper part of each opening 13 by means of suitable screws or bolts, and these 5 wearing plates are so arranged that, when the braking bars are engaging a car wheel, the hold down bars will engage the wearing plates, thereby preventing vertical displacement of the braking bars. It is desirable, 10 however, to permit a slight amount of tipping of the brake beams during engagement of the braking bars with a car wheel in order that the braking bars may engage the car wheels at a higher point, and therefore a 15 more effective point, than would be the case if this tilting did not take place; and, in order to permit this tipping, a slight amount of clearance is provided between the hold down bars and the wearing plates, the amount of 20 this clearance accurately determining the amount of tipping of the braking bars as will be apparent from an inspection of the drawings. One advantage of this method of preventing vertical displacement of the braking bars is that the wearing plates and hold 25 down bars are easily accessible when the braking bars are moved away from the track rails, so that when these parts become worn out, they may be quickly replaced.

30 Pivotedly supported in the trackway are two cranks 16 and 17. The crank 16 carries a pin 20, on which is journaled a driving link 21, the free end of which is provided with an upstanding post 23 which enters a suitable 35 socket 24 in an intermediate beam 9 of braking bar B, as best seen in Figs. 1 and 4. In a similar manner, the crank 17 carries a pin 25 on which is journaled a driving link 26, the free end of which is provided with an up- 40 standing post 27 which enters a suitable socket 24 in an intermediate beam 9 of braking bar C. Since the brake beams 9 of each braking bar are all connected together by means of the associated brake shoes D, it will be 45 apparent that if the crank 16 is rotated in a clockwise direction and the crank 17 in a counter-clockwise direction, the braking bars B and C will both be moved towards the left, but that, if the crank 16 is rotated in a 50 counter-clockwise direction and the crank 17 in a clockwise direction, the braking bars B and C will then both be moved towards the right. The free arms of the cranks 16 and 17 are intended to be connected, by means of 55 links 18, with suitable operating mechanism for rotating the crank simultaneously in opposite directions, such for example, as the operating mechanism shown and described in my copending application for Letters Patent of the United States, Serial No. 307,895, filed 60 September 24, 1928, for railway braking apparatus. This operating mechanism is omitted from the drawings because it forms no part of my present invention. The braking bars B^a and C^a are operated by cranks and

driving links which are not shown in the drawings, but which are similar to those described in connection with the braking bars B and C, these latter cranks being connected with the cranks 16 and 17 by means of links 28 and 29, respectively. 70

Pivotedly supported between each pair of stringers are a plurality of trunnions each designated by the reference character E. Each trunnion E is connected by means of a resilient link F with the adjacent braking bar, the links F being so disposed that when the braking bars are moved to the left, the links will rotate toward the associated track rail, thereby moving all of the braking bars toward the track rails and into effective or braking positions in which they will frictionally engage the wheels of a car passing through the braking apparatus. The trunnions E and resilient links F may have any suitable form, and may for example, be similar to the trunnions D and links G described and claimed in my copending application referred to hereinbefore. Certain of the trunnions E and links F have been omitted from Fig. 1 to simplify the drawings. 80

In the operation of braking apparatus of the type described, it may happen under some conditions that the wheels of a car upon being engaged by the braking bars, are lifted off of the track rails, and ride up on top of the braking bars. When this occurs, it is desirable to guide the wheels of the car back onto the rails at the leaving end of the retarder, in order to prevent the wheels of the car from dropping down into the trackway and damaging the car and lading, or the apparatus located in the trackway, or both. For this purpose, I provide two guide rails G and H which are located between the track rails at 100 the leaving end of the retarder, the adjacent inside brake beams being made slightly shorter than the corresponding outside beams to provide room for the guide rails. 105

The guide rails G and H are similar, and in the form here shown each comprises a casting 30 which is supported by the ties, and which is secured to the ties by means of bolts or lag screws which pass through suitable lugs 30^a formed integral with the casting 110 (see Figs. 2 and 6). As here shown, each casting 30 is provided with a substantially horizontal surface 30^a (see Fig. 6) which is located below the tops of the rails a distance which is slightly less than the depth of a car wheel flange, and with a substantially vertical surface 30^b which extends above the tops of the rails and which is inclined towards the associated rail from a point adjacent the leaving end of the adjacent braking bar, sufficient clearance being maintained at the nearest point of this surface to the rail to permit the passage of a car wheel flange between this surface and the rail. Each casting 30 is also provided with a substantially 120 125 130

vertical surface 30^c which curves towards the rail from a point beyond the leaving end of the retarder, this surface serving as a guide for the wheels of cars or locomotives moving through the retarder in the opposite direction from the normal direction of traffic through the retarder. Furthermore, the casting 30 has a portion cut away at 30^d between the two vertical surfaces 30^b and 30^c to a depth which is just below the top of the rail in order to permit the passage of wide locomotive driving wheels through the retarder.

When the car wheels of a car are raised from the track rails by the braking bars there are several positions which the wheels may take with relation to the braking bars and to the rails. For example, when the braking bars are in their braking positions, the tread of one wheel may ride on top of braking bar B , and the tread of the other wheel may ride on top of braking bar B^a ; or the tread of one wheel may ride on top of an outside braking bar B or B^a , while the tread of the other wheel remains on its track rail or, again, when the braking bars are in either their braking or non-braking positions, the tread of one wheel may ride on top of an outside braking bar such as B and the flange of the other wheel on top of an inside braking bar such as C^a .

In explaining the operation of the guide rails, I will assume that the wheels of a car occupy the positions last mentioned above. Under these conditions, as the car wheels approach the end of the retarder, the flange of the wheel which has been riding on braking bar C^a rolls from the end of this bar onto surface 30^a of guide rail H . As it continues its forward motion, the flange of the wheel on guide rail H engages the vertical surface 30^b , which surface guides it back to its proper position with respect to rail 1^a . The other wheel, which in the meantime has had its tread riding on braking bar B , is urged by the guiding effect imposed on the other wheel, first to the position in which its flange drops on top of rail 1 and, finally, to the position where its tread drops in place on rail 1 . The operation of the guide rails for the other positions of the car wheels pointed out above is similar to that described, and will be readily understood from an inspection of the drawings.

It should be pointed out that, since, as here shown, the two brake beams which are located between the track rails at the leaving end of the retarder are made shorter than the corresponding beams on the outside of the rails to provide room for the guide rails, the beams on the outside of the guide rails in addition to performing their normal breaking function also serve to support the wheels of derailed cars while the cars are being guided back onto the rails by the guide

rails. This construction, however, is not essential to my invention.

It should also be pointed out that with the guide rails constructed and arranged in the manner shown and described, it is impossible for the guide rails to engage dragging equipment on the cars to damage either the cars or the guide rails.

One advantage of railway braking apparatus embodying my invention is that since the brake beams of each braking bar are connected together by means of the brake shoes in the manner described, misalignment of the brake beams is positively prevented and a smooth braking action is insured.

Another advantage of railway braking apparatus embodying my invention is that since the opposed ends of adjacent brake shoe sections are fastened to the same brake beam, there is no tendency to chip the wheels of a car, or to cause shock to the retarder, when a car wheel is passing from one shoe section to the next.

A further advantage of railway braking apparatus embodying my invention is that the number of parts required to drive the braking bars is reduced to a minimum, thereby reducing to a minimum the friction losses, and hence the power required to operate the retarder.

Although I have herein shown and described only one form of railway braking apparatus embodying my invention, it is understood that various changes and modifications may be made therein within the scope of the appended claims without departing from the spirit and scope of my invention.

Having thus described my invention, what I claim is:

1. Railway braking apparatus comprising a fixed yoke extending transversely beneath a track rail and provided with an opening, a brake beam supported by said yoke and movable parallel with and transversely with respect to said track rail, and a hold down bar extending through the opening in said yoke and secured to said brake beam for limiting vertical displacement of said brake beam.

2. Railway braking apparatus comprising a plurality of fixed yokes extending transversely beneath a track rail and each provided with an opening, a brake beam supported by said yokes and movable parallel with and transversely with respect to said track rail, and a plurality of hold down bars one extending through the opening in each yoke and each secured to said brake beam for limiting the amount of vertical displacement of said brake beam.

3. Railway braking apparatus comprising a fixed yoke extending transversely beneath a track rail and provided with an opening, a wearing plate secured to said yoke at the

top of said opening, a movable brake beam supported by said yoke, and a hold down bar extending through said opening and secured to said brake beam in such manner that said hold down bar will engage said wearing plate when said brake beam is moved toward said track rail into a braking position thereby preventing vertical displacement of said brake beam.

4. Railway braking apparatus comprising a plurality of fixed yokes extending transversely beneath a track rail and each provided with two openings, one located on each side of said track rail, a plurality of wearing plates one secured to each yoke at the top of each opening, two brake beams supported by said yokes and one located on each side of said track rail, said brake beams being movable parallel with and transversely with respect to said track rail, and a plurality of hold down bars one extending through the opening in each yoke and secured to an associated one of said brake beams in such manner that said hold down bars will engage said wearing plate when said brake beams are moved toward the track rail into braking positions and prevent vertical displacement of said brake beams.

5. Railway braking apparatus comprising a plurality of fixed yokes extending transversely beneath a track rail and each provided with an opening, a brake beam supported by said yokes and provided with a socket, a member movable transversely of the track rail, a driving link connected with said member and provided with a post which enters said socket, whereby said brake beam is moved in directions parallel with said track rail in response to movement of said member, means effective when said brake beam is moved parallel with said track rail in one direction for moving said brake beam toward said track rail into a braking position, and a plurality of hold down bars one extending through the opening in each yoke and each secured to said beam for preventing vertical displacement of said beam when said beam is in its braking position.

6. Railway braking apparatus comprising a braking bar located in the trackway adjacent a track rail, said braking bar comprising a plurality of aligned brake beams, means operatively connected with one of said brake beams for at times moving said brake beam parallel with said track rail in one direction, a brake shoe connected with all of said brake beams in such manner that movement of said one beam causes corresponding movements of all of said beams, and means effective when said brake beams are moved parallel with said track rail in said one direction for moving said beams toward said track rail.

7. Railway braking apparatus comprising a braking bar made up of a plurality of aligned brake beams located in the trackway adjacent

a track rail and movable parallel with and transversely with respect to said track rail, means operatively connected with one of said brake beams for at times moving said one brake beam in directions parallel to the track rail, a brake shoe connected with all of said brake beams for transmitting motion from said one brake beam to the other brake beams and for engaging a car wheel when said brake beams are moved toward the track rail, and means connected with said brake beams for moving said beams toward the track rail when said brake beams are moved parallel with the track rail in one direction.

8. Railway braking apparatus comprising a braking bar made up of a plurality of aligned brake beams located in the trackway adjacent a track rail and movable parallel with and transversely with respect to the track rail, means operatively connected with one of said brake beams for at times moving said one brake beam in directions parallel with the track rail, a plurality of brake shoe sections, means for attaching said sections to said brake beams in such manner that adjacent brake beams are connected together, said shoes serving to transmit motion from said one brake beam to the remaining brake beams and also to engage a car wheel when said beams are moved toward the track rail, and means connected with said brake beams for moving said brake beams toward the track rail when said beams are moved parallel with said rail in one direction.

9. A braking bar for railway braking apparatus comprising a plurality of aligned brake beams, and a replaceable brake shoe connected with all of said brake beams.

10. A braking bar for railway braking apparatus comprising a plurality of aligned brake beams, and a plurality of brake shoe sections, said sections being attached to said beams in such manner that all of said beams are connected together by means of said shoes.

11. A braking bar for railway braking apparatus comprising a plurality of aligned brake beams, and a plurality of brake shoe sections, said sections being attached to said beams in such manner that each two adjacent beams are connected together by one of said brake shoe sections.

12. Railway braking apparatus comprising a plurality of fixed yokes extending transversely beneath a track rail and each provided with an opening, a braking bar comprising a plurality of aligned brake beams supported by said yokes and connected together by a replaceable brake shoe, an intermediate one of said brake beams being provided with a socket, a crank pivotally supported in the trackway adjacent said braking bar, a driving link operatively connected at one end with said crank and pro-

vided at the other end with a post which enters said socket, means for at times actuating said crank to move said braking bar in directions parallel with said track rail, 5 resilient means effective when said braking bar is moved parallel with said track rail in one direction for moving said braking bar toward said track rail into a braking position, a plurality of wearing plates one secured to each of said yokes at the opening therein, and a plurality of hold down bars one extending through the opening in each yoke and each secured to an adjacent brake beam in such manner that said hold down 10 bars engage said wearing plates when said braking bar is in its braking position and thereby prevent more than a predetermined amount of vertical displacement of said brake beams.

13. The combination with railway braking apparatus comprising braking bars located in the trackway adjacent the track rails and movable into engagement with the wheels of a car for retarding the motion of the car, 15 of a guide rail at the leaving end of the apparatus having a substantially vertical surface extending above the tops of the track rails and inclined toward one track rail from a point adjacent the end of a braking 20 bar associated with said one track rail and also having a substantially horizontal surface extending toward said one track rail from said vertical surface and located a slight distance below the top of said one 25 track rail.

14. The combination with railway braking apparatus comprising braking bars located in the trackway adjacent the track rails and movable into engagement with the 30 wheels of a car for retarding the motion of the car, of a guide rail at the leaving end of the apparatus having a substantially vertical surface extending above the tops of the track rails and inclined toward one 35 track rail from a point adjacent the end of a braking bar associated with said one track rail and also having a substantially horizontal surface extending toward said one track rail from said vertical surface and located below the top of said one track rail a distance which is slightly less than the depth 40 of a car wheel flange.

15. The combination with railway braking apparatus comprising braking bars located in the trackway adjacent the track rails and movable into engagement with the 45 wheels of a car for retarding the motion of the car, of a guide rail at the leaving end of the apparatus having a substantially vertical surface extending above the tops of the track rails and inclined toward one 50 track rail from a point adjacent the end of a braking bar associated with said one track rail and also having a substantially horizontal surface extending toward said one track rail from said vertical surface and located below the top of said one track rail a distance which is slightly less than the depth 55 of a car wheel flange.

zontal surface extending toward said one track rail from said vertical surface and located below the top of said one track rail a distance which is slightly less than the depth of a car wheel flange, sufficient clearance being provided between said guide rail and said one track rail at their closest points to permit the passage of a car wheel flange between said one track rail and said guide rail.

16. The combination with railway braking apparatus comprising braking bars located in the trackway adjacent the track rails and movable into engagement with the wheels of a car for retarding the motion of the car, of two guide rails located between the track rails at the leaving end of the apparatus and one associated with each track rail, each guide rail being provided with a substantially vertical surface inclined toward the associated track rail from a point adjacent the end of a contiguous braking bar and extending above the associated track rail, and with a substantially horizontal surface extending toward the associated track rail from said vertical surface and located a slight distance below the top of the associated track rail, sufficient clearance being provided between each guide rail and the associated track rail to permit the passage of a car wheel flange between such guide rail and the associated track rail.

17. The combination with railway braking apparatus comprising braking bars located in the trackway adjacent the track rails and movable into engagement with the wheels of a car for retarding the motion of the car, of a guide rail located in the trackway adjacent one side of one track rail at the leaving end of the apparatus, said guide rail comprising a first substantially horizontal surface located below the top of said one track rail a distance which is slightly less than the depth of a car wheel flange for receiving car wheels raised from the track rails during the transit of the car through the apparatus, a first substantially vertical surface extending upwardly from said horizontal surface to a point which is above the top of said one track rail and inclined toward said one track rail for engaging the wheels which are received by said first horizontal surface to positively guide the wheels of a derailed car onto the rails, and a third substantially vertical surface inclined toward said one track rail from a point beyond the leaving end of the retarder for guiding car wheels entering the apparatus against the normal direction of traffic, a portion of said guide rail being cut away between said first and second vertical surfaces to a depth which is only slightly below the top of said one track rail to permit the passage of wide locomotive driving wheels between the guide rail and said one

track rail, sufficient clearance being provided between said guide rail and said one track rail at their closest points to permit the passage of a car wheel flange between said guide rail and said one track rail.

In testimony whereof I affix my signature.

HERBERT L. BONE.
